UNITED STATES PATENT OFFICE.

ANTON E. NIELSEN, OF BROOKLYN, NEW YORK, ASSIGNOR, BY MESNE ASSIGNMENTS, TO FISCHER BENTSEN, OF NEW YORK, N. Y.

FARE-REGISTER.

SPECIFICATION forming part of Letters Patent No. 710,796, dated October 7, 1902.

Application filed March 26, 1901. Serial No. 52,884. (No model.)

To all whom it may concern:

Be it known that I, ANTON E. NIELSEN, a citizen of the United States of America, and a resident of New York city, borough of Brooklyn, county of Kings, State of New York, (post - office address 2540 Vernon avenue, Brooklyn, New York,) have invented certain new and useful Improvements in Fare-Registers, of which the following is a specification.

10 My invention relates to improvements in fare-registers, and resides most particularly in means for disconnecting the actuating-train from the registering-train in combination with special means for bringing each indicator of the registering-train to the starting-point or zero and for absolutely preventing any independent movement of the indicators during the period within which they may be brought into unison, together with 15 the concurrent operation of a totalizer. In order to bring the indicators to zero, as on starting a trip or at each end of the run, I provide means whereby the geared connections are thrown out of mesh with the indicators and into engagement with a locking-bar, whereby their position and relation is 20 preserved until the indicators have been brought to zero, when by a reverse movement of the part controlling the position of the connecting gears or pinions referred to they are rocked backward into operative engagement with the gears upon the indicators. By an arrangement which will be described a setting-key is pushed into operative position and 25 then turned to shift and disengage the connecting or transfer pinions between the indicators, which through a sliding part, herein-after referred to as the "locking-plate," is automatically interposed so as to stop the rotation of the indicators when they have reached 30 zero. Said plate has also a latch-groove to prevent it moving backward after the setting-key has been pushed up. This device compels the operator to force the key to and 35 through its full movement, and thereby to bring the indicators to zero before any other manipulation becomes possible.

The above-mentioned, together with other features of the invention, will be hereinafter 40 more fully set forth, together with various details of construction coacting therewith,

some of which are old and well known, reference being had to the accompanying drawings, in which—

Figure 1 is a front elevation of the registering mechanism, the dial being omitted for convenience of illustration. Fig. 2 is a front elevation of the back or wall plate of the fare-register. Fig. 3 is a vertical section of what is shown in Fig. 2 on the line W W. Fig. 4 is a side elevation of the mechanism of the register of Fig. 1 viewed from the left. Fig. 5 is a vertical sectional view on the line X X of Fig. 1, also from the left. Fig. 6 is a vertical sectional elevation of parts of the registering mechanism, taken on the line Y Y of Fig. 1, the same being on the inside of the side plate—that is, looking from the left. Fig. 7 is a side elevation of the mechanism as seen from the right of the same side plate seen 70 from the opposite side in Fig. 6 and showing the setting or zero key with its connections. Fig. 8 shows one of the indicators together with the locking-pawl and zero-stop. Fig. 9 is a detail showing the setting or zero key, 75 connecting-slide, locking-plate, automatic latch therefor, and a portion of one of the indicator-wheels. Fig. 10 is a detail section on the line Z Z of Figs. 1 and 9. Fig. 11 is a plan view of the spider fitted in the interior of each of the indicator-wheels. Fig. 12 is a view on the line y y of Fig. 1, showing the indicator transfer-gear and its rocking support similar to that in Fig. 5, but from the opposite side. Fig. 13 is a detail showing a 80 modified form of connection between the connecting-slide actuated by the setting-key and the gear-shifting lock-plate shown separately in Fig. 9. Fig. 14 is a fragmentary view, in horizontal section, showing a portion of the 85 main shaft, the main ratchet, pinion, and gear which are rotatably mounted upon said shaft and pinned so as to move together.

Referring to the drawings, as indicated in Fig. 2, 1 is a wall-plate, usually of metal, 90 which is provided with an ear 2 at its upper side and a pair of lugs 3 at its lower side, between which is held and supported the base-plate 4 of the machine, Fig. 1, said plate being provided at its upper side with a slotted 95 extension 5, adapted to fit over the ear 2, and with a projection 6, adapted to be secured be-

tween the lugs 3 of the wall-plate 1. Plate 1 carries mechanism for communicating the step-by-step movement from the usual conductors's pull-strap or rotating rod, (not shown,) but which is connected to the rod 7 in the well-known manner. The connecting-rod 7 is pinned to one arm of a bell-crank lever 8, the opposite extremity 9 of which abuts against a slide 10, provided with an extension 11, which engages a pin or projection 12, connected with the actuating mechanism of the registering-train. A suitable retracting-spring 13 is provided for returning the slide 10 to normal position, and with it the bell-crank, the connecting-rod 7, and its actuating devices.

Upon the base-plate 4 (see Fig. 1) is mounted a frame comprising principally the side plates 14 15, which form the support for the registering mechanism. At the lower end of the machine, as indicated in Fig. 1, is shown a registering-train composed of five registering-wheels or indicators 16 17 18 19 20. These wheels may or may not be permanently exposed to view, as preferred, and constitute what is known as the "totalizer," being a counting-train which is at all times in operative connection with the unit impulse device operated as fares are collected, so as to register every movement thereof. The impulse device is locked when the indicators are being set to zero, so that the totalizer is not affected by that operation. This part of the mechanism is, however, in common and well-known use for this purpose and constitutes no part of the present invention. The wheels 16 17 18 19 20 are mounted loosely upon common shaft 21. Indicating characters from 0 to 9 are marked upon the peripheral surfaces of each of the wheels and each is provided with a gear-wheel 22 23 24 25 26, rigidly attached and interposed between itself and the next. On the inner side of the four wheels 17 18 19 20 of the totalizer-train is attached a disk 27 28 29 30, in each of which there is a single notch or depression 31 to engage the transfer-gear. In front of the disks of the totalizer-train is mounted a stationary shaft 32, upon which are loosely mounted four transfer-pinions 33 34 35 36, which are permanently in mesh with the gears 22 23 24 25 and are provided at intervals with extra wide or transfer teeth 37, which said teeth engage the notches or depressions 31 as the wheels are turned and move the engaged adjacent wheels to the extent of one character or number. This is repeated in the ordinary operation of the machine, as is well understood, so that when suitably adjusted the unit-wheel will turn ten times to the decimal-wheel's one, and so on through the train to indicate addition up to tens of thousands.

In the present instance the end wheel of the totalizer-train is provided with a strong steel gear 26, which meshes with an intermediate or idler gear 39, which meshes with the pinion 40, connected to the unit or step-by-

step impulse device actuated by the conductor in the operation of ringing up fares.

The unit-registering train, actuated step by step by the conductor, is represented by three indicator-wheels 41 42 43, each of which is provided upon its periphery with numerals "0," "1," "2," "3," "4," "5," "6," "7," "8," and "9" and operatively connected by transfer-gearing to indicate addition in the well-known manner—in this instance from zero to hundreds. These indicators are mounted upon main through-shaft 44, which is formed with a keyway or slot 45 and is normally stationary, but is rotated by special means whenever it is desired to bring the indicators to zero.

Upon the interior of each of the indicators 41 42 43 is secured a spider 46, which may be variously constructed, but, as indicated in Figs. 8 and 11, is provided with four arms 47 48 49 50 and a forward stop 50^a and a back-stop 59^a. Upon the arms of the spiders of the indicators 41 42 are secured disks 41^a 42^a, each having a single peripheral notch 4^a, coinciding with the teeth of the adjacent gear-wheel upon the next indicator. Indicator-wheel 41 is provided on its opposite side with gear 51 and indicator-wheels 42 and 43 with similar gear 52 53, all of the same mesh. Three transfer-pinions 54 55 56 normally engage with these gears and are rotatably mounted upon the shaft 57, carried in arms 57^a 57^b, pivoted upon a rock-shaft 57^c. The pinions 54 and 55 each have extra large teeth 4^b at intervals to engage the notches 4^a upon the gears 52 53 at each revolution thereof, as is well known. A transfer-wheel or driver-gear 58 is mounted to turn upon the main shaft 44, as is also a transfer-pinion 40 and the main ratchet 63. The driver-gear 58, pinion 40, and ratchet 63 are secured together, so as to always turn as one, as indicated in Fig. 14. The driver-gear 58 coincides in size and mesh with the gear 51, attached to the indicator 43, and is close to it. Both said gears are engaged during the operation of the mechanism by the transfer-pinion 56, (referred to as the coupler,) the teeth of said pinion being all alike and of the width of the combined teeth of both the wheels 51 and 58. Being so united, the motion transmitted to the transfer-wheel 58 by the rotation of the main ratchet as the fares are rung up will transmit motion to the gear 51 on the indicator 41, and thence from one indicator to another through the transfer-pinions 55 54, as stated. Upon one of the arms of each spider 47 is pivoted a spring-pawl, hereinafter referred to as "zero-stop" 59, the outer extremity of which projects normally a very short distance through a slot in the periphery of the indicator, but is extended farther when the indicators are brought to zero. The forward stop 50^a of the spider 47 limits the forward movement of the zero-stop, and the back-stop 59^a is provided with an adjusting-screw 59^b. The inner end of the screw 59^b is in

the path of the lower end of the zero-stop pawl 59, and by means thereof the extent of the rearward movement of said pawl can be adjusted to compensate for wear or irregularity in size, so that the indicators will be in line when the zero-stops engage and are forced full up against the under side of the locking-plate. To another arm of each of the spiders is attached a locking-pawl 60, which is adapted to engage in the slot or keyway 45 in the main shaft 44 to prevent other rotation of said shaft than is necessary to bring the indicators to zero, when the setting mechanism returns to its inactive position, locking said main shaft against rotation until it is again rotated by the setting mechanism to turn the indicators to zero, they, the indicators, being then disconnected from their driving-gear and frictionally connected with 50 the periphery of the said shaft through the pawls 60.

The construction of the pawl 60 is such that it can rise or be drawn out of the keyway in one direction only—viz., that which will permit the indicators to be turned by their geared connection to the driver-gear in the direction to register to indicate addition. When the registering impulse of rotation is imparted to an indicator through the driver 55 and transfer gear, with which the gears attached to the indicators are normally in mesh, and therefore positively engaged, said pawl will rise out of the keyway and be turned about the stationary main shaft 44 with its indicator, to which the pawl is attached. In this way the indicators 41 42 43, each similarly provided with pawls 60, are turned forward upon the stationary main shaft step by step by the impulse mechanism operated by 60 the conductor in registering fares. When the main shaft is rotated by the setting mechanism, the frictional engagement of the pawls 60, pressing upon the main shaft 44, is sufficient to turn the indicators around with said shaft until they are all stopped and positively held at zero by their zero-stops 59. This brings the pawl 60 into line, and by such further small movement of the shaft as may be necessary to bring the keyway into line thereupon all of the pawls 60 will again engage it, and further rotation of said shaft by the setting mechanism be prevented. The setting mechanism cannot now be turned any farther in either direction and is free to and 65 must be allowed to return to its inactive position before the registering mechanism can again be operated, as will appear. The movement of the main ratchet also imparts movement to the pinion 40, secured thereto and through it, and the idler 39 connects said main ratchet with the totalizing-train and the steel gear 26 upon the disk 20 of said train. Mounted upon the base-plate 4 is a slide 61, which, as stated, has a pin 12 70 extending through the plate to engage the projection 11. Upon this slide and secured to a suitable standard 61^a is an upwardly-

spring-pressed dog 62, which normally engages from its under side the main ratchet 63, which is rotatably mounted upon the shaft 70 75 44. With each actuation of the registering mechanism the slide is forced upward, and the dog turns the ratchet to the extent of one tooth, and with it the driving-gear 58 and pinion 40, and through the coupler-pinion 56, 75 the gear 51, indicator 41, and the connected indicator-train.

A swinging lever 64 is mounted upon the shaft 44, concentric with the ratchet 63, and carries at its upper end a pawl 65 and also at 80 its upper extremity a shutter 66, which is indicated in dotted lines in Fig. 1, and acts to indicate full or partial registration and when in fully-operated position to cover the figure last registered upon the unit-indicator 85 43.

The swinging lever 64 is free to move and turns on the main shaft 44, where it is placed between the main ratchet 63 and the inside of the side plate 15. A spring 68, attached 90 to the upper part of the said lever and to a fixed portion of the frame (best seen in Fig. 1) tends normally to draw its upper end forward and to bring the shutter over the figure to be indicated by the movement of the registering-train, which permits the movement of the shutter-lever under stress of spring 68. The lever moves back and the figure is disclosed by connection between its lower portion and the main actuating-slide 61. This 100 connection is shown in Fig. 6 in the form of a spring hook or catch 67, which is attached to the standard 61^a and engages a projection 67^a on the lever 66 and travels forward with the pawl 62, permitting the spring 68 to pull 105 the upper part of the swinging lever, with its shutter and the dog 65, downward as the said slide 61 is moved upward during the act of registering a fare. The downward movement of the lever 66 and shutter is limited by a 110 second projection 67^b on the lever engaging a stop 67^c on the side plate 15. A third dog or detent 69 engages the main ratchet-wheel 63 upon its upper or front side, as indicated most clearly in Fig. 6. This detent is formed 115 at one end of a two-arm lever, which is pivoted at 70, and has an upward-extending part or arm 71, which extends to and engages an offset 73 in pivoted lever 73^a, which carries the bell-ringing hammer 73^b and is provided 120 with an operating-spring 73^c. The bell 73^d is in position to be struck by the hammer when retracted by its spring 73^c and is indicated at 73^e. A short distance in the rear—that is, at the base of the downwardly-extending arm of lever 71, which forms the detent 69—is a projection 72, by which, in connection with the locking-plate, the main ratchet is locked in inoperative position when the indicators are being set to zero, as will 130 appear.

When the slide 61 is moved through a full stroke, the dog 62, engaging the ratchet 63, imparts movement thereto sufficient to turn

one of the indicators one-tenth of a revolution, and in so doing the detent 69 is lifted, the extension 71 is thrown downward, the bell-lever 73^a actuated, and the bell rung. 5 Coincidentally the lever 64 swings downward, and its pawl 65 falls upon the advance face of the last exposed tooth of the ratchet 63. The bell having been rung, the lever 71 will have risen to its normal position and the detent 69 become fully seated in the tooth of the ratchet 63, in which position the pawl carried by the swinging lever 64 will ride over the detent 69 and in that way return to its normal position; but if, on the other hand, 10 15 the movement is only partially made, whether from accident or design, the bell will not have been rung, the detent 69 will not be able to seat itself in the tooth of the ratchet on account of the position of the bell-ringing lever 71 and will project up far enough to catch the pawl 65, carried by the swinging lever 64 on its attempted return, and this pawl will hold and prevent further movement of the detent 69 and in that manner 20 25 completely lock the registering mechanism and prevent it from being operated either to count or to ring until the original movement which was interrupted is completed, while at the same time the shutter 66 will cover about 30 one-half of the figure upon the indicator, which on proper registration would be fully exposed.

As stated, each registration of the machine is indicated upon the totalizer.

35 Note: Numerals 74 to 81, inclusive, are applied to a direction-indicating device herein-after referred to.

During each trip and as fares are rung up the indicators are rotated step by step to register each fare, the figures being visible through suitable openings in a front dial, omitted for convenience of illustration. At the end of each trip it is desired to obliterate the record on the indicators and to bring 40 45 them back to zero, which is accomplished by substantially the following means: A device which I have termed the "locking-plate" 82 is arranged close to the faces of the indicators 41 42 43 and is provided with three notches 46 50 55 60 65 70 75 80 85, which are in the paths of the three spring-pawls, "zero-stops" 59 and normally allow them to pass in the rotation of their indicators under registering impulses without hindrance. Similarly a larger notch 86 is provided to admit of the necessary movement of the bell-ringing lever 71, a projection 72 upon which is especially adapted to enter said notch as the registering mechanism is actuated. The rock-shaft 57 carries 55 60 65 70 75 80 85 arms 57^a 57^b, united by a non-rotating shaft 57^c, upon which are rotatably mounted the transfer-pinions 54 55 56. A mechanical connection is made between the locking-plate 82 and the arms and shaft carrying the transfer- 65 70 75 80 85 gears 54 55 56, so that upon the movement of the plate said arms are rocked or moved away from the indicators to disengage the transfer-

pinions from the gear-wheel carried by the said indicators. As shown, this function may be conveniently performed by a pin 87, moving in a reversely-curved slot 88 in the locking-plate 82. A setting-key 89 is located at the side of the machine and is connected with an endwise-movable rod 90, which is mounted in bearings 91 92, extending from or rigidly attached to the side plate 15. A pair of spaced disks 93 94 are secured near the base of said rod 90 and are provided with coinciding notches 95, which are adapted, when the rod 90 is retracted, to engage a stationary plate 96, 80 whereby their rotation is prevented and the said rod cannot be turned. A sliding plate 97 is supported upon the top of the extension 92, near one end, and upon a separate extension 92^a, near its other end, where it is suitably held by screws passing through longitudinal slots therein. The back of the plate 97 is provided with a downwardly-extending pin 98, fitting the space between the disks 93 94, through which it is connected with the endwise-moving rod 90, so that when the latter is pushed forward or upward the plate 97 moves therewith. In the upper extremity of the plate 97 is an angular slot 99, which engages a pin 100 upon the end of the locking-plate 82, whereby when the plate 97 is pushed up lateral movement is imparted to the said locking-plate. As a means for diminishing friction the slide-plate 97 instead of being provided with angular slot 99 may, as shown in Fig. 13, have pivotally attached at its upper end a small bell-crank 101, connected to the said plate 97 by a pin 102, extending from the said plate and engaging a notch 103 in the one end of the bell-crank, the connection 105 with the locking-plate 82 being through a similar pin and catch 104 105. The extension 92 also carries a spring-pawl 106, engaging ratchet-wheel 107, which ratchet is secured to a bevel-gear 108. The two being rotatably supported within the extension 92 are bored out to permit the free endwise movement of the upper end of the rod 90 therein and have a fixed key engaging a corresponding slot or keyway in the said rod 110 115 120 125 130 135 140 145 150 155 160 165 170 175 180 185 190 195 200 205 210 215 220 225 230 235 240 245 250 255 260 265 270 275 280 285 290 295 300 305 310 315 320 325 top of the machine downward. By the movement just described the locking-plate 82 has been shifted laterally, so that all of the notches which previously permitted the gear-5 stops 59 of the indicators and the extension 72 on the detent 69 to pass freely and the bell-hammer lever 71 also to be actuated are displaced, solid metal taking their place, while at the same time the frame carrying the trans-10 fer-pinions 54 55 56 has been moved away from the indicators, disengaging said gearing therefrom and engaging the same with a locking-strip 110, by which the said transfer-pin-15 ions are held in proper position to be returned correctly into mesh with the gearing upon the indicators when they have been brought into unison at zero. The setting-key having been pushed up, by turning it the main shaft is rotated, and with it the indicators 41 42 43, 20 which will be turned, respectively, until their zero-stop pawls catch under the unnotched portions of the locking-plate 82, which is then in their path, and they will be held by the said pawls until all are in the same position—25 namely, at zero—when by engagement of the locking-pawls 60 with the keyway on the main shaft 44 the setting-key can be no longer turned and moves back into its normal position under stress of suitable spring 111, at-30 tached to slide-plate 97 and to a stationary part 112 of the frame. In this position the notches 95 in the disks 93 94 engage the plate 96 and lock this part of the apparatus until it is desired to repeat the cycle of operations 35 just described. When the setting-key 89 has been pushed upward a portion of its full movement, return to its original position without completing the cycle of operation which brings the indicators to zero is prevented. 40 This is accomplished by the interposition of a small pawl or catch 114, extending outwardly across the edge of said plate and carried by a pivotally-supported downwardly-spring-pressed arm 113, which fits under the 45 lock-plate 82. A notch 115 is formed in the edge of the plate 82, and the normal position of the pawl 114 is so near to the end of the notch that a very short lateral or locking movement of the plate 82 is sufficient to al-50 low it to drop therein. When in position the pawl 114 prevents retraction of the said plate 82 until the pawl 114 has been pushed out of the way. This is accomplished automatically when the indicators come to zero by 55 the extremity of the spring-pawl 59 of the indicator 43, which, striking the under side of the plate 82 before the same has been retracted to its normal position impinges against said plate, is tilted up, and engages 60 the edge of the arm 113, as indicated in Fig. S. In being so tilted the zero-stop 59 pushes back the arm 113, thereby lifting the pawl 114 out of the notch 115 and permitting the retraction of lock-plate 82, when the several 65 notches will resume their first position and all of the zero-stops be free. Coincidentally with this return the notches 95 in disks 93 94

have engaged stationary plate 96, thereby preventing rotation of the setting-key in either direction. The main shaft now becomes stationary, being locked by the setting mechanism, and more particularly through disks 93 94 and plate 96, and the indicators can only be operated through their exterior connections, the slide 10, the main ratchet 63, and 70 the gear 58, which connects with the indicators through the first one of the transfer-pin-ions 56, the pinion 40 acting through the idler 39 to operate the totalizing-train above referred to. Improper operation of the apparatus under these conditions, as already pointed out, is prevented by interference with the return of the detent 69, attached to the bell-operating lever, unless the full stroke is made, which will ring the bell, and thereby give the 85 desired signal, at the same time operating the indicators. It is also indicated by the failure of shutter 66 to fully expose the last number registered. 90
In order to indicate the direction of the trip the car is about to make, a direction-indicating shutter 74 is provided and actuated each time the setting-key is employed to return the indicators to zero, as explained. The shutter 74 is attached to the free end of a lever 75, which is pivotally supported upon pin 76, screwed to the side plate 14 of the machine. A driving-pinion 77 is placed upon the main shaft 44 and meshes with a crank-wheel 78, also rotatably mounted upon said 95 plate 14. The crank-wheel is provided with a wrist-pin 79, and a similar pin 80 is attached to the shutter-carrying lever 75, said pins being united by connecting-rod 81. The diameters of these pins being properly proportioned the crank-wheel will make one-half a revolution each time the indicators are brought to zero, and thereby through connecting-rod 81 will move the shutter-carrying lever to its extreme forward or extreme 100 backward position. If, therefore, the words "east," "west," or the like be placed upon the shutter in parallel lines, one or other will be brought opposite of the opening in the face-plate, and so indicate the direction in which 105 the car is traveling. 110
While I have described the mechanism of my fare-register in detail, it must be understood that various minor changes and modifications may be made in the shape and construction of the parts without departing from 115 my invention as pointed out in the claims, and, furthermore it is to be understood that where it is desired to register both cash fares and transfers complete duplicate sets of indicating and totalizing mechanism are employed. The operating parts of the machine are all the same except that the main shaft is extended to receive and carry the second set 120 of mechanism and the locking-plate is ex-125 tended to perform the functions herein described with two sets of mechanism instead of one, both being set to zero by the one setting-key, as set forth. The particular con-130

ditions of the parts will be determined by the particular use to which the apparatus is to be applied. 135

struction of the parts, their arrangement, and the mode of operation of the duplex machine remain in all essential respects the same as the single, as hereinbefore described.

5 Having described my invention, what I claim is—

1. In a fare-register, the combination of indicators having attached actuating gear-wheels and mounted on and rotatable in one direction only on a normally stationary main shaft having a frictional connection with said indicators, a driver-gear actuated by the registering mechanism, transfer-gearing positively connecting the same and also transferring movement from one indicator to the next, and means for simultaneously disconnecting the transfer-gears from the indicator and driver gears to permit separate movement of the indicators and interposing a locking device for stopping the indicators at zero, and means for holding said gears in fixed position, and for returning said transfer-gears into engagement with the indicator-gears.

2. A fare-register comprising indicators mounted on and rotatable in one direction only on a normally stationary main shaft having a frictional connection with said indicators each indicator provided with operating-gear, a step-by-step actuating mechanism provided with a driver-gear, transfer-gearing connecting the indicators and coupling the driver-gear in positive relation thereto, and means for temporarily disconnecting the transfer and coupling gear from the driver and indicators to permit separate movement of the latter when set to zero and simultaneously interposing a stop for locking said indicators at zero.

3. In a fare-register, the combination with rotatable geared indicators each provided with a zero-stop and mounted on and rotatable in one direction only on a normally stationary main shaft having a frictional connection with said indicators, a driver-gear, transfer-gears connecting said indicators and the driver in positive geared relation, a movable support for the transfer and connecting gear, a locking-plate normally permitting the free rotation of the indicators, a stop connected with the support of the transfer and connecting gear and adapted to be displaced by movement of the locking-plate to disengage the transfer and connecting gear when the indicators are turned to zero.

5. In a fare-register, the combination with a slide carrying an upwardly-spring-pressed pawl and means for imparting reciprocating motion thereto at each registration, of a normally stationary main shaft rotatable in one direction only and having a frictional connection with the indicators, and adapted to turn said indicators to zero, a main ratchet and a driver-gear moving with said ratchet and rotatably supported upon the main shaft, a series of indicators each provided with actuating-gear and mounted upon and rotatable upon said main shaft during registration, a

corresponding series of detachable transfer-gearing engaging and positively connecting said indicators, the first of said transfer-gear engaging and connecting the driver-gear and the adjacent indicator-gear for transferring the registering impulse from the driver-gear to the indicators.

5. In a fare-register, the combination with a slide carrying an upwardly-spring-pressed pawl and means for imparting reciprocating motion thereto at each registration, of a normally stationary main shaft rotatable in one direction only and having a frictional connection with the indicators, and adapted to turn said indicators to zero, a main ratchet and a driver-gear moving with said ratchet and rotatably supported upon the main shaft, a series of indicators each provided with actuating-gear and mounted upon and rotatable upon said main shaft during registration, a corresponding series of detachable transfer-gearing engaging and positively connecting said indicators, the first of said transfer-gear engaging and connecting the driver-gear and the adjacent indicator-gear for transferring the registering impulse from the driver-gear to the indicators, and means for locking the indicators when set to zero and for simultaneously locking the main ratchet when setting the indicators.

6. In a fare-register, indicators mounted on and rotatable in one direction only on a normally stationary main shaft having a frictional connection with said indicators and each provided with operating-gear, a step-by-step actuating mechanism, transfer-gearing connecting the indicators and engaging gearing operated by the step-by-step mechanism, a totalizer and a geared connection between the step-by-step mechanism and the totalizer-train whereby the indicators and the totalizer are normally in operative geared relation, and means for temporarily disconnecting the transfer-gear from the indicators and locking the indicators at zero, and for separately rotating said indicators to zero and for again connecting the transfer-gearing therewith and releasing the indicators.

7. In a fare-register, the combination with a part adapted to be reciprocated during the movement of registration and carrying a spring-pressed pawl, a main shaft carrying registering mechanism, a main ratchet upon said shaft in engagement with and operated by the pawl, a swinging lever mounted concentric with the ratchet and connected with the reciprocated part and carrying a visual signal or shutter, whereby the signal is exposed to an extent corresponding with the movement of the reciprocating part and ratchet.

8. In a fare-register, the combination with a slide carrying a pawl and means for reciprocating the slide with each registration impulse, a ratchet adapted to operate registering mechanism, a pivoted bell-hammer lever, a pivoted two-armed lever, one arm of which

operatively engages the bell-hammer lever, its other arm resting upon and operated by and forming a detent for the ratchet upon the completion of each registering movement, a 5 swinging lever concentric with the ratchet and carrying a pawl at its free end, said pawl being in the path of the detent-arm and adapted upon a partial return movement to engage and lock said arm and registering mechanism 10 when but a partial registering stroke has been made.

9. In a fare-register, the combination of a reciprocating slide, a spring - pressed pawl thereon and means for reciprocating the slide 15 with each registration, a main shaft, a ratchet rotatably mounted thereon and in engagement with said pawl, for operating registering mechanism, a bell-ringing lever, a pivoted lever, one part of which engages the bell- 20 ringing lever, its other part forming a detent for the ratchet, a swinging lever also mounted concentric with the main shaft and carrying a pawl arranged in the path of the detent and adapted upon the completion of the full stroke 25 of registration to pass over the detent on the return movement of said lever.

10. In a fare-register, the combination with registering mechanism, a main ratchet connected therewith and means for communicating step-by-step motion thereto, a pivoted bell-ringing lever, a pivoted lever operatively engaging the bell-ringing lever and also engaging and actuated by the ratchet and acting as a detent therefor on completion of the 35 registering stroke, a normally inactive locking device and means for moving the same into the path of the bell-ringing lever and detent, and thereby locking the registering mechanism when desired.

40 11. In a fare-register, the combination with registering mechanism, of a slide carrying a pawl and means for reciprocating the slide with each registration impulse, a ratchet adapted to operate the registering mechanism, 45 a bell-ringing lever, a pivoted two-armed lever, one arm whereof operatively engages the bell-ringing device, its other arm resting upon and in operative relation to the ratchet and its extremity forming a detent therefor upon 50 the completion of a registering stroke, and having also a projection upon said last-mentioned arm, a locking device normally out of the path of the projection of the detent-arm, and a setting-key and connections for moving 55 the locking device into position to obstruct the moving of the detent-arm and lock the registering mechanism when desired.

12. In a fare-register, the combination of suitable indicators having projections arresting 60 them all at the desired point, means comprising a locking-plate normally out of the path of the projections to permit rotation of the indicators under the impulse of registering mechanism, said locking-plate means being adapted to be displaced to engage the 65 projections upon the indicators when desired to bring them to zero.

13. In a fare-register, the combination with suitable indicators each having a zero-stop whereby they may be all brought to zero, a 70 locking-plate provided with notches adapted to normally permit the free rotation of the indicators and a passage of the notches when said indicators are impelled by the registering impulses and means for displacing the 75 plate and notches to engage the zero-stops when the indicators are returned to bring them to zero.

14. In a fare-register, the combination with suitable indicators each provided with an adjustable zero-stop, a locking-plate normally permitting the free rotation of the indicators and stops and adapted to be displaced to engage the stops when the indicators are turned 80 to zero. 85

15. The combination with indicators and means for turning the same step by step upon a stationary shaft to register, as desired, transfer-gearing in mesh with said indicators and with the actuating mechanism and connecting them in positive geared relation, means for locking the indicators at zero, a setting-key and means actuated thereby for disconnecting the transfer-gearing, actuating the locking mechanism and rotating the indicators to 95 zero. 90

16. In a fare-register, the combination with indicators and transfer-gearing for communicating motion from one to the other, a normally stationary main shaft supporting said 100 indicators thereon rotatable in the direction for registration, a zero-stop connected with each indicator, a locking-plate having notches arranged to permit the passage of the zero-stops during registration, and means for displacing the plate and notches and for rotating the main shaft together with all of the indicators until they are brought to zero and their movement is arrested by the pawls engaging the plate. 105 110

17. In a fare-register, the combination with a transfer-gear and suitable actuating mechanism, rotatably-mounted indicators each provided with a gear, a gear connecting the driver-gear with one of the indicator-gears 115 and transfer-gearing connecting the remainder of the series of indicators, a movable support for the connecting and transfer gearing and a locking-bar for engaging the movable gear when disengaged from the indicators 120 and driver whereby the engaging positions of said gear are maintained until they are moved back into operative position.

18. In a fare-register, the combination of a normally stationary main shaft, indicators 125 mounted thereon and normally rotatable in the direction for registration, transfer-gear positively connecting the indicators, a normally locked setting-key adapted to turn the main shaft, a locking-plate normally out of 130 locking position and connections between said plate and the setting-key whereby the same can be moved into locking position, connections between the locking-plate and the trans-

fer-gearing connecting the indicators whereby when the setting-key is moved into operative position, the locking-plate is displaced to stop the indicators at zero and throw the transfer-gears out of mesh with the indicators.

19. In a fare-register, the combination of a normally stationary main shaft, indicators mounted thereon and rotatable in the direction for registration, transfer-gear positively connecting the indicators, a normally locked setting-key adapted to turn the main shaft, a locking-plate normally out of locking position and connections between said plate and the setting-key whereby the same can be moved into locking position, connections between the locking-plate and the transfer-gearing connecting the indicators, whereby when the setting-key is moved into operative position the locking-plate is displaced to stop the indicators at zero and throw the transfer-gears out of mesh with the indicators, and an automatic latch adapted to engage the locking-plate in mid-position to prevent retraction until the setting operation has been completed.

20. In a fare-register, the combination of a normally stationary main shaft, indicators mounted thereon and normally rotatable in the direction for registration, transfer-gear positively connecting the indicators, a normally locked setting-key adapted to turn the main shaft, a locking-plate normally out of locking position and connections between said plate and the setting-key whereby the same can be moved into locking position, connections between the locking-plate and the transfer-gearing connecting the indicators whereby when the setting-key is moved into operative position the locking-plate is displaced to lock the indicators at zero and throw the transfer-gear out of mesh with the indicators, and means for limiting the rotation of the setting-key to one direction when in operative position, and means for locking the setting-key against rotation when in its normal, inoperative position.

21. In a fare-register, the combination with indicators having zero-stops, a locking-plate arranged in proximity to the indicators and normally out of the path of the stops, a set-

ting-key for moving the locking-plate into position to engage the zero-stops and an automatic latch adapted to engage the locking-plate to prevent retraction thereof until the setting operation has been completed, and a part connected with said latch and extending into the path of one of the said stops, whereby it is automatically released.

22. In a fare-register, the combination of a normally stationary main shaft having a keyway therein, indicators each provided with a zero-stop and with a spring-pawl adapted to engage the keyway, means for rotating the indicators upon the shaft and for lifting the pawl out of the keyway and into frictional engagement with the main shaft when the indicators are turned in the direction for registration, and setting mechanism for rotating the main shaft and indicators and for arresting the zero-stops and indicators as the latter reach zero and for further rotating the main shaft until the spring-pawls reengage the keyway and stop the setting mechanism.

23. In a fare-register, the combination with a normally stationary main shaft, indicators rotatably mounted thereon, and normally connected by transfer-gearing, each indicator provided with a spring-pawl in frictional engagement with said main shaft and a zero-stop for each indicator, a locking-plate arranged in proximity to the peripheries of the indicators and provided with notches permitting the passage of the zero-stops during registration, a setting-key rotatable in one direction and connected with the main shaft for turning the same, but normally locked from rotation, means connected with the setting-key for displacing the locking-plate so as to engage the zero-stops of the indicators and simultaneously disconnect the transfer-gearing and for rotating the main shaft and indicators until the latter are arrested at zero by their stops and the main shaft and setting-key are stopped by the reengagement of the spring-pawls with the keyway therein.

Signed by me at New York, N. Y., this 15th day of March, 1901.

ANTON E. NIELSEN.
